[57] CLAIM

The ornamental design for a combined food holder and carving aid, as shown and described.

DESCRIPTION

FIG. 1 is a side elevational view of a combined food holder and carving aid showing my new design, the side opposite being a mirror image thereof;
FIG. 2 is a front elevational view thereof;
FIG. 3 is a rear elevational view thereof;
FIG. 4 is a top plan view thereof; and
FIG. 5 is a bottom plan view thereof.

FIG. 1

FIG. 2

FIG. 3

FIG. 4

FIG. 5
